MACHINE FOR FORMING AND APPLYING
LIQUID SPRAY

William K. Andrew, Wauwatosa, Wis.

Application June 27, 1935, Serial No. 28,657

22 Claims. (Cl. 91—44)

This invention relates to spray forming and directing apparatus, more especially for applying liquids over the surface of materials in the form of separate drops or spray, and particularly to a form of device which provides for continuous operation on moving materials.

In the past materials have been sprayed by operation of an air blast directed against the material to be treated. Such operation has a variety of objectionable features. It does not produce uniform size or distribution of the individual spray particles. It tends to rapidly evaporate the sprayed material. Perhaps one of the most objectionable features of air blast spray operation is the spray material which is carried away by the moving air, whereby anything adjacent to the surfaces which it is desired to spray also becomes coated. Suction devices to avoid this effect are not practicable because any sufficiently strong suction destroys or diverts the spray.

It is a purpose of this invention to overcome these and various other objectionable features of previous spray devices.

Another purpose of the invention is to provide improved means for forming a spray of finely divided particles of liquid material.

A further purpose relates to improved means for controlling the average size of the individual particles of a sprayed material, and for producing a uniform distribution thereof.

A further purpose is to provide improved means for directing the sprayed material and for controlling the area to be sprayed thereby, particularly where the spray is applied to moving materials.

A further purpose is generally to simplify and improve the construction and operation of spray machines and machines for similar and analogous uses, and still other purposes will be apparent from the specification.

The invention consists in the construction and combination of parts as herein illustrated, described and claimed and in such modifications of the structure described as may be equivalent to the structure of the claims.

The same reference characters have been used throughout to indicate the same parts, and in the drawings:

Fig. 1 is an end elevation of a structure incorporating the invention, and of a portion of a supporting structure therefor.

Figure 2 is a plan view, partly in section, taken approximately along line 2—2 of Fig. 1.

Fig. 3 is a section taken approximately along line 3—3 of Fig. 2, and enlarged.

Fig. 4 is an enlarged partial section taken approximately along line 4—4 of Fig. 1.

Fig. 5 is a side elevation of the portion of the structure shown at the lower right of Fig. 2, as viewed from the right.

Fig. 6 is an enlarged partial section taken along line 6—6 of Fig. 3.

Fig. 7 is an enlarged partial section along line 7—7 of Fig. 2.

The machine here shown includes a support 1, which may be a portion of the structure of a printing press, or other machine for traversing paper or other material to which liquid is to be applied. Support 1 carries feeding rolls 2, 3, for guiding and traversing a strip or band of material such as 4, the material being in this instance further guided by a table or platen 5. It will be understood that the material 4 is traversed endwise as by rotary motion applied to roll 2 from a suitable source, not shown.

A housing or casing 6 is carried by or adjacent to the support 1 and within the housing are a plurality of axially parallel roll members 7, 8, 25 disposed transversely to the direction of movement of the strip 4. The roll 7 is carried in suitable fixed bearings, such as the bearing 9, respectively at opposite ends of the casing 6, and of a form restraining the roll from axial movement. Roll 8 is similarly restrained against axial movement by a plurality of bearings such as 10, but in this instance each bearing is mounted in an eccentric carrying member, such as 11, which may be adjusted to alter the center distance of rolls 7, 8, by the means of segment arms, such as 12, fixed on each eccentric member and each engaging pinions, such as 13, respectively fixed at opposite ends of a shaft 14, the shaft having a squared end portion 15, to which a suitable crank, 40 not shown, may be applied.

The roll 7 is driven in the direction of the arrow, Fig. 1, at a relatively high peripheral speed from a suitable source such as a motor 16, the drive in this instance being through pulleys 17, 45 18, and a belt 19.

The roll 8 is also driven, but may be at a relatively much lower rate, preferably oppositely to roll 7, and at a variable rate. As here shown, roll 8 is driven from motor 16 through pulleys 20, 21 and belt 22, a speed reducer generally denoted by the numeral 23, which may be of any conventional form, and a rate change device generally denoted by the numeral 24, which includes a belt 25 having angular sides comple- 55

mentary to angular faced pulley portions 26, 27, mounted on a shaft 28 of the speed reducer 29 and axially movable relative to one another, the pulley portions being continuously urged axially 5 toward one another by a spring 29. Belt 25 engages a pulley 24a fixed on the extended end of roll 8 and is adapted to drive while engaging the pulley portions 26, 27 at various effective driving diameters, which may be changed by 10 changing the center distance of shaft 28 and roll 8, the change being made by bodily adjusting the speed reducer by the means of a threaded bolt 30 and nuts 31, 32, the speed reducer being pivoted for movement about the axis of the shaft 15 of motor 16 on the arms 33, 34. By the adjustable pulley means described the speed of roll 8 may be changed in the ratio of two or three to one, or even more.

Both the roll 8 and roll 7 are peripherally 20 grooved throughout their larger diameter with relatively closely spaced annular grooves, such for instance as 35, 36, as shown in Fig. 6, the position of the rolls being such that the grooves engage less or more as determined by the adjustment of the eccentric members 11. The roll 7 is also axially grooved, their being relatively fine grooves forming teeth such for instance as are indicated at 37 in Fig. 1, extended axially 25 through the large diameter and closely spaced 30 around the entire periphery, the grooves being preferably in the form of saw teeth pointed in the direction of rotation of the roll.

Casing 6 provides a well or reservoir portion 35 such as 38 constantly supplied with liquid by suitable means such for instance as a supplemental reservoir 39 containing liquid which is pumped into reservoir 38 at low pressure by a pump 40 driven from a motor 41, and through an inlet 42 having a baffle 43, surplus liquid being 40 returned to reservoir 39 through an overflow pipe 44, which is adjustable for altering the height of liquid in reservoir 38 by the means of nuts 45, 46.

The liquid in reservoir 38 contacts roll 8 less 45 or more, according to the adjustment of overflow 44, and a film of liquid is continuously carried by roll 8 to the point where rolls 7, 8 are nearly in peripheral contact, at which point some of the liquid is sheared off by the rapidly moving 50 saw teeth of roll 7 in the form of very fine particles or drops varying in size according to the adjustment of overflow 44, the speed of roll 8 and the adjustment of the one roll relative to the other. These particles are of constant and uniform 55 individual size as long as the various adjustments remain unchanged, the particles being of very fine size for the ordinary purposes of the machine.

The particles of liquid, by reason of the relatively high speed of roll 7, and in part by reason 60 of the relative disposition of the rolls, are driven off substantially tangentially and substantially at right angles to the common plane of the roll centers, to form a band of spray particles substantially uniformly distributed through an angular space somewhat as indicated at 47, in Fig. 1, extending the entire length of the toothed portion 65 of the rolls and without any material disturbance of the adjacent air.

The liquid particles or spray passes out of the 70 casing 6 through an elongated shutter opening between wall surfaces 48, 49, Fig. 3, so disposed that the liquid in reservoir 38 will not overflow therethrough, and the spray is directed downwardly, in this instance onto the moving strip

or band 4. For many purposes, as for instance where the band 4 is to be uniformly covered or sprayed with liquid the mechanism thus far disclosed would be sufficient, particularly if in addition to the spray regulating means described 5 there were utilized some of the various well known means, not shown, for varying the linear speed at which the band 4 is traversed, whereby to further control the amount of liquid spread per unit of area of the band 4.

But for many purposes, it is desirable to add 10 other control mechanisms as follows.

A manually adjustable shutter, generally denoted by the numeral 50, is operable to control the width of the liquid spray in the direction 15 of the movement of band 4. Shutter 50 includes a fixed member 51, and a member 52 adjustable toward or from member 51 by manipulation of knobs or handles such as 53, 54, similarly connected with member 52 by means such as rods 20 55, pins 56 and pin engaging members 57 which are fixed on member 52, there being detent means associated with the rods, such as the spring pressed plungers 58 engaging with one or the other of notches 59. When the member 52 is 25 adjusted to overlap the member 51 no spray will pass out of the casing 6 and all the sprayed liquid will return to reservoir 38 through suitable channels within the casing.

The manually adjustable shutter 50, to some 30 extent, provides means answering the same purpose as would a change in the speed of the band 4. If the shutter is adjusted for a narrow spray band the effect in reducing the amount of liquid applied per unit of area of band 4 is approximately the same as would be obtained by a suitable increase in the speed at which the band passes through the spray zone 47, and vice versa.

An automatically controlled shutter is also provided, which is generally denoted by the numeral 40 60. Shutter 60 includes a shutter member 61 movable toward and from the fixed member 51 by the means of a shaft 62 which, at each end thereof, carries arms such as 63, having pins such as 64 engaging members such as 65 fixed with the 45 member 61. Shaft 62 is oscillated to open and close shutter 60 in predetermined timed relation with the linear movement of band 4, through mechanism providing for a variety of changes in the timing and in the opening and closing movements.

The mechanism connecting shutter 60 for automatic movement includes a mechanical train as follows. A gear 66 fixed on the shaft 67 of roller 2 engages a gear 68 fixed on a shaft 69. Shaft 55 69 drives a shaft 70 through a timing device or rate changer generally denoted by the numeral 71, which comprises a plurality of reversible and interchangeable replaceable gear pairs of different ratio, which are adapted to be removably fixed 60 on the ends of shafts 69, 70, the gears 72, 73 illustrating one of the gear pairs, and together providing any desired ratio of shaft 70 to the linear movement of band 4.

Shaft 70 drives a cam 74 through meshed gears 75, 76, the cam being frictionally fixed for angular adjustment on a shaft 74a, by the means of a nut 74b. Cam 74 has suitable configurations for movement of a follower roll 77 carried by a pivoted lever 78 which carries a pivot 79 for movement of a rod 80, the follower roll 77 being continuously pressed against cam 74 by a spring 81. Rod 80 is connected for movement of a rod 82 by a turn buckle device 83 in which the adjustable member 83a engages oppositely threaded 75

ends on the rods 80, 82. Rod 82 is pivoted at 84 on a member 85 which is adjustable on a lever arm 86 by the means of a screw 87, the arm 86 being fixed on the shaft 62.

5 By the means of the mechanism just described the shutter 60 can be opened and closed at predetermined spaced intervals in the movement of band 4, the number of such opening and closing movements per linear unit of band movement being determined by the rate change device 71, and may also be varied if desired by changing the 10 number of lobes or depressions provided in cam 74. The width of opening of shutter movement can be adjusted by the screw 87 and can also be determined by the depth of the depressions in 15 cam 74. The slope of the depressions in cam 74 may be varied to effect either abrupt or gradual opening and closing of the shutter 60. The relative 20 position of the movement of shutter member 52 can be readily adjusted by the adjustment of the turnbuckle device 83, whereby the shutter 60 may be completely closed to overlap member 51 at one point in its movement or may be partly 25 open at its most nearly closed position.

25 In many instances the manual shutter 50 will be fully open during the use of the automatic shutter 60. In other instances it will be found desirable to control the maximum width of the spray during operation of the automatic shutter by adjusting shutter 50 to a point where it 30 limits the maximum spray width.

It may also be noted that the automatic opening and closing of shutter 60 need not be used unless desired or necessary. Thus, if the gear pair 35 72, 73 is removed, or the shutter 60 otherwise disconnected from roll 2, the shutter 60 becomes merely a manually operable shutter which may be adjusted for various widths of shutter opening by the means of the screws 87, 83a, or other suitable 40 means.

It will, of course, be obvious that either or both of the shutters 50, 60 may be made in sections separately adjustable, whereby to individually control different portions of the spray path or zone 45 in the direction of the axis of the rolls. Such construction would merely require shorter sections for the shutters and a duplication of the adjusting means shown, and is therefore not shown in detail.

50 In many instances it is desirable to maintain the sprayed liquids at predetermined temperatures, higher than room temperatures. This might be true in order to control the rate at which a sprayed liquid will dry out on the material of band 4, or in instances where the material of the spray is normally solid or too viscous to form an effective spray until heated. The material in the auxiliary reservoir 38 may be maintained at desired temperatures by any suitable well known means, not shown. For heating the material within the reservoir 38 there is provided electric heating means including resistance wires, such as strip 88 having insulated resistance 5 wires 89. A number of such heating elements may be arranged at various points inside or outside the walls of casing 6.

Additional heating means may be provided for each of the rolls 7, 8, consisting of a plurality of insulated resistance wires, such as 90, 91, carried by the rolls. These wires may be carried in suitable drilled holes if desired, but are here shown fixed in channels or grooves such as 90a, 91a, the grooves being closed to provide a substantially unbroken roll surface by the means of

members such as 90b, 91b, retained by screws such as 90c, 91c.

For supplying current to the resistance elements 90, 91, each of the rolls 7, 8 is provided with commutator devices such as 92, which may 5 include commutator segments such as 93, to which current is supplied by brush devices such as 94, there being similar commutator and brush devices, not shown, for the roll 7. It will be understood that the commutators provide annularly spaced segments in oppositely disposed pairs, the different segments of a pair being respectively connected with different ends of a resistance wire unit, the segments and wires being insulated from the rolls. Also that the brushes are spaced 10 in pairs similarly to the segments, the different brushes of a pair being respectively connected to the different terminals of a current supply source and each insulated from the frame, all 15 in the usual manner for such devices. 20

It will be understood that the casing 6 and rolls 7, 8 may be of any desired length depending upon the desired width of the spray.

For access to the rolls 7, 8, and to the interior of casing 6, there is provided a hinged cover 95. 25 When cover 95 is closed the entire spray mechanism is enclosed, and only the spray itself is projected outside the casing, there being substantially no movement of air into or out of the 30 casing.

By reason of the avoidance of air current, both in forming and projecting the spray, the sprayed particles are confined almost completely to the area upon which they are permitted to be projected by the shutters 50, 60, this area being very 35 sharply defined. The surrounding air is substantially completely free of spray or particles of material sprayed, since there is little or no air movement to carry the spray particles. 40

What is claimed is:

1. In a spray forming machine, the combination of a rotatable feed roll carrying liquid and another rotatable roll non-contactingly adjacent thereto, said other roll providing rigidly spaced saw-like teeth, said rolls being positioned for 45 said teeth during rotation to pick up separate particles of the liquid carried by said feed roll, and means for rotation of said rolls at speeds adapted to continuously feed said liquid and to tangentially eject said particles. 50

2. In a spray forming machine, the combination of a rotatable feed roll carrying liquid, another rotatable roll adjacent thereto, said other roll providing spaced mutually transverse grooves forming saw-like teeth, said rolls being positioned 55 for the individual teeth to separate individual particles of the liquid carried by said feed roll, and means for rotation of said rolls at speeds and in relative directions adapted to continuously feed said liquid and to eject said liquid particles 60 in a path simultaneously substantially tangent to both said rolls.

3. In a spray forming machine, the combination of a rotatable annularly grooved feed roll carrying liquid, another rotatable roll adjacent 65 thereto, and providing rigidly spaced teeth engaging the feed roll grooves, said rolls being positioned for the individual teeth during rotation to separate individual particles of the liquid carried by said feed roll, means for rotation of said rolls 70 at speeds and in relative directions adapted to continuously feed said liquid and to eject said liquid particles in a path simultaneously substantially tangent to both of said rolls, and shutter means in said path and operative to control 75

the spray width in said simultaneously tangent path.

4. In a spray forming machine, the combination of a rotatable feed roll carrying liquid, another rotatable roll non-contactingly adjacent thereto, said other roll providing teeth rigidly fixed therewith in predetermined axial and annular spacing, said rolls being positioned for the individual teeth during rotation to separate individual particles of the liquid carried by said feed roll, means for rotation of said rolls at speeds and in relative directions adapted to continuously feed said liquid and to eject said liquid particles in a path simultaneously substantially tangent to both of said rolls, and shutter means mounted in said simultaneously tangent path, to control the width of the spray of ejected particles in said path.

5. In a spray machine, the combination of a rotatable feed roll carrying liquid, another rotatable roll adjacent thereto, said other roll providing teeth rigidly fixed therewith in predetermined axial and annular spacing, said rolls being positioned for the individual teeth during rotation to separate individual particles of the liquid carried by said feed roll, means for rotation of said rolls at speeds adapted to continuously feed said liquid and to eject said liquid particles in a path simultaneously substantially tangent to both of said rolls, shutter means mounted in said path and adjustable for a preferred width thereof, and timing means operative to open said shutter means to said preferred width and alternatively to close said shutter means at predetermined intervals.

6. In a spray machine, the combination of a rotatable feed roll carrying liquid, another rotatable roll adjacent thereto, said other roll providing teeth rigidly fixed therewith in predetermined axial and annular position, said rolls being positioned for the individual teeth during rotation to separate individual particles of the liquid carried by said feed roll, means for rotation of said rolls at speeds and in directions adapted to continuously feed said liquid and to eject said liquid particles in a path simultaneously substantially tangent to both of said rolls, and means for traversing material to be treated by said particles through said path.

50 7. In a spray machine, the combination of a rotatable feed roll carrying liquid, another rotatable roll adjacent thereto, said other roll providing teeth rigidly fixed therewith in predetermined axial and annular position, said rolls being positioned for the individual teeth during rotation to separate individual particles of the liquid carried by said feed roll, means for rotation of said rolls at speeds and in relative directions adapted to continuously feed said liquid and to eject said liquid particles in a path simultaneously substantially tangent to both of said rolls, means for movably supporting material to be treated by said particles in a position to intercept said path, means for traversing said material through said path, shutter means adjustably interposed in said path between said material and said rolls and means for adjusting said shutter means to control the width of said path outside said shutter means in the direction of movement of said material.

8. In a spray forming machine, the combination of a rotatable feed roll carrying liquid, another rotatable roll adjacent thereto, said other roll providing teeth rigidly fixed therewith in predetermined axial and annular position, said rolls being

positioned for the individual teeth to separate individual particles of the liquid carried by said feed roll, means for rotation of said rolls at speeds and in directions adapted to continuously feed said liquid and to eject said liquid particles in a path simultaneously substantially tangent to both of said rolls, means for movably supporting material to be treated by said particles in a position to intercept said path, means for moving said material through said path at uniform speed, shutter means movably mounted in said path between said material and said rolls, and timing means for opening and closing said shutter means at intervals timed relative to the movement of said material.

9. In a spray forming machine, the combination of a rotatable feed roll carrying liquid, another rotatable roll adjacent thereto, said other roll providing teeth rigidly fixed therewith in predetermined axial and annular position, said rolls being positioned for the individual teeth to separate individual particles of liquid carried by said feed roll, means for rotation of said rolls at speeds and in directions adapted to continuously feed said liquid and to eject said liquid particles in a path simultaneously substantially tangent to both of said rolls, means for movably supporting material to be treated by said particles in a position to intercept said path, means for moving said material through said path at uniform speed, shutter means movably mounted in said path between said material and said rolls, timing means for opening said shutter means at intervals timed relative to the movement of said material, and means adjustably controlling the effective width of minimum and maximum shutter opening.

10. In a spray forming machine, the combination of a reservoir containing liquid, a rotatable feed roller engaging said liquid and having annular grooves, another rotatable roller having annular grooves and having transverse grooves forming together with the annular grooves a multiplicity of spaced peripheral teeth, said rollers being positioned for said teeth to engage the grooves of the feed roller, means for rotation of said feed roller at a rate sufficient to feed said liquid to engage said teeth, and means for rotation of said other roller at a rate sufficient to throw off said liquid from said teeth in separated particles in a path substantially tangent to both said rollers.

11. In a spray forming machine, the combination of a reservoir containing liquid, a rotatable feed roller engaging said liquid and having annular grooves, another roller having annular grooves and having transverse grooves forming together with the annular grooves a multiplicity of spaced peripheral teeth, said rollers being positioned for said teeth to engage the grooves of the feed roller, means for rotation of said feed roller at a rate sufficient to feed said liquid to engage said teeth, means for rotation of said other roller at a rate sufficient to throw off said liquid from said teeth simultaneously tangentially to both said rollers and in separated particles, and means for changing the average quantity of liquid in said particles.

12. In a spray forming machine, the combination of a reservoir containing liquid, a rotatable feed roller engaging said liquid and having annular grooves, another rotatable roller having annular grooves and having transverse grooves forming together with the annular grooves a multiplicity of spaced peripheral teeth, said rollers

being positioned for said teeth to engage the grooves of said feed roller, means for rotation of said feed roller at a rate sufficient to feed said liquid to engage said teeth, means for rotation 5 of said other roller at a rate sufficient to throw off said liquid from said teeth simultaneously tangentially to both said rollers and in separated particles, and means for changing the relative rate of rotation of one of said rollers.

13. In a spray forming machine, the combination of a reservoir containing liquid, a rotatable feed roller engaging said liquid and having annular grooves, another rotatable roller having annular grooves and having transverse grooves forming together with the annular grooves a multiplicity of spaced peripheral teeth, said rollers being positioned for said teeth to engage the grooves of said feed roller, means for rotation of said feed roller at a rate sufficient to feed said liquid to engage said teeth, means for rotation of said other roller at a rate sufficient to throw off said liquid from said teeth substantially tangentially to both said rollers and in separated particles, and means for adjusting the center distance 15 of said rollers.

14. In a spray forming machine, the combination of a reservoir containing liquid, a rotatable feed roller engaging said liquid and having annular grooves, another rotatable roller having annular grooves and having transverse grooves forming together with the annular grooves a multiplicity of spaced peripheral teeth, said rollers being positioned for said teeth to engage the grooves of said feed roller, means for rotation of said feed roller at a rate sufficient to feed said liquid to engage said teeth, means for rotation of said other roller at a rate sufficient to throw off said liquid from said teeth simultaneously substantially tangentially to both said rollers in separated particles, means for adjusting the center distance of said rollers, and means for adjusting the relative rate of rotation of one of said rollers.

15. In a spray forming machine, the combination of a hollow casing, a reservoir containing liquid within said casing, a rotatable feed roller engaging said liquid and having annular grooves, another roller having annular grooves and having transverse grooves forming together with the annular grooves a multiplicity of uniformly spaced peripheral saw-like teeth, said rollers being positioned for said teeth to engage the grooves of said feed roller, means for rotation of said feed roller at a rate sufficient to feed said liquid to engage said teeth, and means for rotation of said other roller at a rate sufficient to throw off said liquid from said teeth substantially tangentially to both said rollers and in separated particles, said casing providing an opening in said tangential path and determinative of the width of the stream of particles outside said casing.

16. In a spray forming machine, the combination of a hollow casing, a reservoir containing liquid within said casing, a rotatable feed roller engaging said liquid and having annular grooves, another rotatable roller having annular grooves and having transverse grooves forming together with the annular grooves a multiplicity of spaced peripheral teeth, said rollers being positioned for said teeth to engage the grooves of said feed roller, means for rotation of said feed roller at a rate sufficient to feed said liquid to engage said teeth, means for rotation of said other roller at a rate sufficient to throw off said liquid from said teeth substantially tangentially to both said

rollers and in separated particles, adjustable shutter means providing an opening in said casing for the ejection of said particles outside said casing, and means movably supporting material to be treated in the path of particles ejected through said shutter means.

17. In a spray forming machine, the combination of a hollow casing, a reservoir containing liquid within said casing, a rotatable feed roller engaging said liquid and having annular grooves, another rotatable roller having annular grooves and having transverse grooves forming together with the annular grooves a multiplicity of spaced peripheral teeth, said rollers being positioned for said teeth to engage the grooves of said feed roller, means for rotation of said feed roller at a rate sufficient to feed said liquid to engage said teeth, means for rotation of said other roller at a rate sufficient to throw off said liquid from said teeth substantially tangentially to both said rollers and in separated particles, shutter means providing an opening for the ejection of said particles outside said casing, means for the movable support of material in the path of said ejected particles, means for the movement of said material at uniform rate, and means for operating said shutter at intervals timed relative to the rate of movement of said material.

18. In a spray forming machine, the combination of a hollow casing, a reservoir containing liquid within said casing, a rotatable roller within said casing having annular grooves and having transverse grooves forming together with the annular grooves a multiplicity of spaced peripheral teeth rigidly fixed in predetermined axial and annular position, means to feed said liquid to engage said teeth, means for rotation of said roller at a rate sufficient to throw off said liquid from said teeth in a path tangential to the point at which the liquid is applied thereto and in separated particles, shutter means providing an adjustable opening for the ejection of said particles outside said casing, means for movably supporting material in said path, means for the movement of said material through said path at uniform rate, timing means for operation of said shutter at intervals timed relative to the rate of movement of said material, and means for changing the relative timing of said shutter means.

19. In a machine for forming a liquid spray, the combination of a rotatable roll having peripheral saw-shaped teeth rigidly fixed in predetermined axial and annular position adapted to separately receive fluid particles, means for continuously applying said particles to said teeth, and means for rotation of said roll at a speed sufficient to separately continuously throw off said particles tangentially to the point received by said teeth.

20. The method of forming a liquid spray which includes feeding the material to be sprayed to the points of saw-like teeth rigidly fixed and spaced on a rotating roller and rotating the roller at a speed sufficient to throw off substantially all of the applied liquid substantially at the instant applied and in a path substantially tangential to the point of application thereof.

21. In a spray forming machine the combination of a rotatable feed roll having axially spaced annular grooves carrying liquid to be sprayed, another rotatable roll non-contactingly adjacent said feed roll and having peripherally spaced teeth arranged in axially spaced sets respectively operative in the different axially spaced feed roll grooves to pick up liquid therefrom, and means

for rotation of said rolls at speeds and in directions for said teeth to continuously pick up and tangentially eject separate particles of said liquid.

22. The method of forming a liquid spray which includes continuous rotation of an annularly grooved feed roller carrying liquid to be sprayed

and tangentially ejecting particles of said liquid from another roller having peripherally spaced teeth in axially spaced sets respectively non-contactingly engaging the different grooves of said feed roller.

WILLIAM K. ANDREW.
